ATTORNEY

UNITED STATES PATENT OFFICE.

LOUIS NAGY, OF HAMILTON, ONTARIO, CANADA, ASSIGNOR OF ONE-FIFTH TO
MICHAEL DARADICS.

NONsinkable SHIP.

Application filed June 22, 1927. Serial No. 200,569.

This invention relates to a new and useful device in the nature of a non-sinkable ship, comprising pontoons attached thereto, and a means of lowering the said pontoons during 5 rough weather or a heavy sea, so as to prevent the sinking or capsizing of the ship.

The object of the invention is to provide a non-sinkable ship of novel construction and arrangement of parts, hereinafter more fully 10 described, claimed, and illustrated in the accompanying drawings.

Fig. 1 is a side elevational view of a non-sinkable ship constructed according to this invention.

Fig. 2 is a front elevational view thereof, showing the pontoons in a raised position.

Fig. 3 is a similar view showing the pontoons in a lowered or in use position.

Fig. 4 is an enlarged fragmentary sec- 20 tional view, taken on the line 4—4 of Fig. 5.

Fig. 5 is a top plan view of my improved non-sinkable ship.

Fig. 6 is an enlarged fragmentary sec- 25 tional view, taken on the line 6—6 of Fig. 5.

Fig. 7 is a fragmentary view similar to Fig. 4 but illustrating a modification of the invention.

As here embodied my improved non-sink- 30 able ship comprises a ship 10 of any desired tonnage, such as ordinarily used for passengers or freight, preferably of the ocean going type, and equipped with pontoons 11 and 12 of hollow construction and of air-tight structure. The pontoons 11 and 12 are 35 hingedly mounted to the sides of the ship 10 by rods 13 and brackets 13' so as to be positioned in proximity to the water line of the ship and extending longitudinally and parallel to the ship.

Link members 14 are pivotally arranged 40 on rods 15 secured to brackets 15' attached to the outer edges of the pontoons, and also pivotally connected to rod 16, and to other link members 17, pivotally connected to rods

18 secured to brackets 18' attached to the 45 sides of the ship. The flexible members 19 and 20 are secured to rods 15 and extend over the guide pulleys 21, secured to the shafts 23' rotatively mounted in the brackets

50 24' attached to the deck of the ship 10. The flexible members 19 and 20 engage onto drums 22 attached to the rod 21' rotatively mounted on the brackets 22' attached to the deck of the ship.

55 Several towers project from the ship 10,

and these towers consist of vertical rods 24 joined at their top ends by plates 25. Slide members 26 are arranged between the rods, and tongues 27 project from the slide members. Connecting levers 28 have their upper 60 ends pivotally secured to tongues 27, and their lower ends to rods 15. Flexible members 29 are secured to the slide members 26 and to drums 30 rotatably mounted to plates 31 attached to rods 24. Gears 32 and 33 65 connect the drums 30 to receive rotation from the shaft 21'. The bottom ends of rods 24 are connected to plates 34, and brackets 35 attach the plates to the boat 10.

The boat 10 is provided with a propeller 70 36 on a driver shaft 37 having a bevel gear 38 meshing with another bevel gear 39 on shaft 40 supported by bracket 41. The shaft 40 is provided with a clutch arrangement 42, and a second bevel gear 43 on shaft 75 40 meshes with a gear 44 on shaft 45 connected with a gear speed reduction mechanism in box 46, which also connects with shaft 21'. A lever 46' projects from the box 46 and connects with the gears within the 80 box so that by movement of the lever, the gears move to reverse the drive connection with shaft 21'. A large link 47 is inserted through the front of the boat, and small links 48 connect the ends of the large link 85 to the pontoons. Chains 49 are connected at their lower ends to the rods 13 and are provided with hooks 50 at their upper ends, normally engaged on pins 51 projecting from the side of the ship. Hooks 52 are 90 pivotally arranged on rods 18 and engage rods 15 to hold the pontoons in raised position. Vacuum pumps 53 are mounted on the ship, and flexible hoses 54 therefrom with check valves 55 connect to the pontoons. 95 Plates 56 reinforce the boat 10 at points where stresses are obtained due to the various apparatus mounted on the sides of the boat.

The operation of the device consists in 100 normally arranging the pontoons in raised position shown in Figs. 1, 2, and 5. The air from within the pontoons may be withdrawn to make them more buoyant. The pontoons may be lowered by releasing hooks 52 from 105 rods 15, moving lever 46' to cause shaft 21' to turn anti-clockwise as seen looking at Fig. 2, and moving clutch 42 so that rotation from the driver shaft 37 is communicated to shaft 21'. Gears 32, 33 communicate this 110

rotation to drum 30 and flexible member 29 winds onto this drum, drawing slide 26 downwardly, forcing rods 28 to move the pontoons to the lower position shown in Fig. 3. Drums 22 on shaft 21' turn leaving flexible members 19 and 20 slack to permit this operation. When the pontoons reach the lowered position the clutch 42 is disengaged. The hooks 50 are disengaged 10 from the pins 51 and engaged onto rods 16 to hold the pontoons in lowered position. The pontoons may be raised by moving control 46' to cause shaft 21' to turn clockwise as seen looking at Fig. 2. The drums 22 draw the flexible members 19, 20 to raise the pontoons, while drums 30 allow the flexible members 29 to be slack and permit the said raising of the pontoons.

The modification of the invention illustrated in Fig. 7 discloses a means for adjusting the upper ends of rods 28 so as to change the normal positions of the pontoons. The slide 26' has projecting portions 26^a and a plurality of tongues 26^b. Auxiliary slide members 58 have one of their ends engaged in grooves 59 and their other ends are pivotally connected to the upper ends of rods 28. Screws 60 are rotatively arranged in the tongues 26^b, and held against displacement by plates 61 attached to the bottom of portions 26^a and 26^b, and these screws threadedly engage the auxiliary slides 58. The ends of the screws are equipped with lock nuts 62 to normally lock the screws from turning. The screw may be turned to cause the auxiliary slides to move therewith, and change the position of the rods 28.

While I have illustrated and described the preferred form, construction, and arrangement of the several elements employed, it will be understood that the device is, nevertheless, susceptible of considerable modification therein, and I have therefore reserved the privilege of resorting to all such changes as may be fairly embodied within the spirit and scope of the invention as claimed.

Having thus described my invention what I claim as new and desire to secure by Letters Patent of the United States is as follows:

1. In combination with a ship, pontoons hingedly mounted to the sides of the ship in proximity to the water line of the ship, rods secured on the pontoons on the sides remote from the sides hingedly connected to the ship, link members pivoted to the rods, other rods secured through the free ends of the link members, other link members connected 55 to the second mentioned rods, still other rods secured to the sides of the ship, and the free ends of the second mentioned link members

being pivotally arranged on the last mentioned rods, flexible members secured to the first mentioned rods, and provided with 65 means for drawing or slackening these flexible members, towers projecting from the ship, slides arranged on the towers, connecting levers arranged between the slides and the first mentioned rods, flexible members secured to the slides and provided with 70 means for drawing or slackening these flexible members.

2. In combination with a ship, pontoons hingedly mounted to the sides of the ship in 75 proximity to the water line of the ship, rods secured on the pontoons on the sides remote from the ship, link members pivoted to the rods, other rods secured through the free ends of the link members, other link members connected to the second mentioned rods, still other rods secured to the sides of the ship, and the free ends of the second mentioned link members being pivotally arranged on the last mentioned rods, hook members pivotally mounted on the last mentioned rods and engageable with the first mentioned rods when the pontoons are in raised position, flexible members secured to the first mentioned rods, and provided with 85 means for drawing or slackening these flexible members, towers projecting from the ship, slides arranged on the towers, connecting levers arranged between the slides, and the first mentioned rods, flexible members secured to the slides and provided with 90 means for drawing or slackening these flexible members.

3. In combination with a ship, pontoons hingedly mounted to the sides of the ship in 100 proximity to the water line of the ship, rods secured on the pontoons on the sides remote from the ship, link members pivoted to the rods, other rods secured through the free ends of the link members, other link members connected to the second mentioned rods, still other rods secured to the sides of the ship, and the free ends of the second mentioned link members being pivotally 105 arranged on the last mentioned rods, flexible members secured to the first mentioned rods, and provided with means for drawing or slackening these flexible members, towers projecting from the ship, and consisting of vertical rods joined at their top ends by 110 plates, slides arranged between the said vertical rods, connecting levers arranged between the slides and the first mentioned rods, flexible members secured to the slides and provided with means for drawing or slackening these flexible members.

In testimony whereof I have affixed my signature.

LOUIS NAGY.
